US00D668740S

(12) **United States Design Patent**
Kulikov et al.

(10) **Patent No.:** **US D668,740 S**
(45) **Date of Patent:** **** Oct. 9, 2012**

(54) **FILTER DEVICE**

(75) Inventors: **Vladimir Mikhailovich Kulikov,**
Moscow (RU); **Vladimir Alekseevich**
Zakharov, Moscow (RU)

(73) Assignee: **DWT Deutsche Wassertechnologien**
GmbH, Frankfurt am Main (DE)

(**) Term: **14 Years**

(21) Appl. No.: **29/404,377**

(22) Filed: **Oct. 20, 2011**

(51) **LOC (9) Cl.** **23-01**

(52) **U.S. Cl.** **D23/209**

(58) **Field of Classification Search** **D23/207,**
D23/209; 210/282, 497.01, 323.1, 323.2

See application file for complete search history.
